Term of patent 14 years

(Cl. D62—2)

Fig. 2

Fig. 3

Fig. 4

FIGURE 1 is a perspective view of a plasma sprayer employing my new design;

FIGURE 2 is a front elevational view thereof;

FIGURE 3 is a rear elevational view thereof;

FIGURE 4 is a perspective view of a plasma sprayer shown in FIGURE 1 taken from the rear and slightly from the bottom thereof.

The dominant features of the design reside in the portions shown in full lines.

The side not shown is substantially the same in appearance as that shown in FIGURE 1.

I claim:

The ornamental design for a plasma sprayer, as shown and described.
